UNITED STATES PATENT OFFICE.

WILLIAM B. KIRKPATRICK, OF CANTON, OHIO.

HAY-LOADER.

SPECIFICATION forming part of Letters Patent No. 622,859, dated April 11, 1899.

Application filed March 31, 1898. Serial No. 676,000. (No model.)

To all whom it may concern:

Be it known that I, WILLIAM B. KIRKPATRICK, a citizen of the United States, residing at Canton, in the county of Stark and State 5 of Ohio, have invented certain new and useful Improvements in Hay-Loaders; and I do hereby declare that the following is a full, clear, and exact description of the same, reference being had to the annexed drawings, making a part of this specification, and to the figures of reference marked thereon, in which—

Figure 1 is a perspective view. Fig. 2 is a view showing a portion of one of the side members and illustrating one of the apron-catches. 15 Fig. 3 is a side elevation. Fig. 4 is a vertical section of the loader. Fig. 5 is a view showing a portion of the frame and showing one of the adjustable bearings for the compound crank-shaft. Fig. 6 is a view showing the top 20 or upper end of one of the elevating-bars, also showing the adjustable cross-bars. Fig. 7 is a detached view of the supporting-bars and their different attachments. Fig. 8 is a detached view of the sliding head and its rod. 25 Fig. 9 is a detached view of the spring. Fig. 10 is a transverse section of the upper cross-bars, showing a longitudinal section of one of the supports and guides or ways.

The present invention has relation to hay-loaders; and it consists in the different parts 30 and combination of parts hereinafter described, and particularly pointed out in the claim.

Similar numbers of reference indicate corresponding parts in all the figures of the drawings.

In the accompanying drawings, 1 represents the traveling wheels, which are mounted upon the axle 2 in the usual manner, to which axle 40 are attached the upright bars or supports 3 and the rearward-extending bars 4, to which the side pieces or members are attached in the usual manner.

To the rear ends or portions of the bars 45 4 are connected slotted uprights 5 and 6, said uprights being preferably formed integral with the plate or bar 7.

To the uprights 6 are adjustably attached the compound crank-shaft bearings 8, said 50 bearings being located substantially as shown in Fig. 5.

The compound crank-shaft 9 is located

transversely across the bottom or lower portion of the frame proper and to which compound shaft the rake-bars 10 are journaled 55 in the usual manner.

Below the rake-bars 10 are located the slats 11, which slats are supported upon the cross or tie bars 12. To the bottom or lower ends of the rake-bars 10 are connected the rake- 60 heads 13, which rake-heads are provided with the teeth 14.

To the side members 15 are attached the uprights or posts 16, which uprights or posts are provided with the slots 17, through which 65 slots are passed the clamping-bolts 18, said clamping-bolts being for the purpose of holding the cross-bars 19, which cross-bars are located substantially as shown in Fig. 1.

To the cross-bars 19 are attached the guides 70 and supports 20, said guides and supports being located and arranged substantially as shown in Fig. 1 and are for the purpose of holding and guiding the top or upper ends of the rake-bars 10, as hereinafter described. 75

To the top or upper ends of the rake-bars 10 are attached the arms 21, to which arms are journaled the rollers 22, said rollers resting upon the top faces of the guides 20, as 80 illustrated in the drawings.

Between the cross-bars 19 are located the rollers 23, which rollers are journaled to the brackets 24, said brackets being securely attached to the guides 20 or their equivalents.

For the purpose of providing a means for 85 moving the cross-bars 19 to or from the slats 11 said cross-bars are adjustably connected to the posts 16 by means of the clamping-bolts 18.

It will be understood that as the cross-bars 90 19 are moved in either direction they will carry with them the guides 20, thereby providing a means for adjusting the space between the slats and the rake-bars 10, thereby providing for the proper handling of different 95 kinds of hay.

When it is desired to change the adjustment of the cross-bars 19, together with the different parts connected to said cross-bars, the clamping-bolts are released, after which 100 the cross-bars are free to be moved up or down, as desired, and when brought to the desired point of adjustment said clamping-bolts are tightened.

For the purpose of adjusting the compound crank-shaft 9 to or from the slats 11, together with the rack-bars journaled thereto, the bearings 8 are adjustably attached to the 5 slotted uprights 6, said bearings being held at the desired point of adjustment by means of clamping-bolts 25, which clamping-bolts are passed through the slots 26.

For the purpose of causing the compound 10 crank-shaft to be rotated in the opposite direction from that of the traveling-wheels 1 the driving-chains are carried under the sprocket-wheels 27 and around the idlers 28, said idlers being located at the rear of the 15 sprocket-wheels 27 and being journaled upon the shafts or spindles 29, which spindles are carried by the bearings 30, said bearings being adjustably connected to the posts or uprights 5 and being held at the desired point of 20 adjustment by means of the clamping-bolts 31.

For the purpose of moving the bearings 8 and 30 in unison the connecting-bars 32 are provided, which bars are attached to the bolts holding the bearings. To the top or upper 25 ends of the posts or uprights 5 are pivotally attached the levers 33, which levers are connected to the connecting-bars 32, substantially as shown in Fig. 5, and when it is desired to elevate the bearings, so as to change 30 the position of the crank-shaft with reference to the slats 11, the bearings are loosened and the rear ends of the levers 33 pressed downward until the bearings have been brought to the required height, after which the clamping-bolts are tightened. 35

It will be understood that by means of my peculiar arrangement I am enabled to adjust both the lower and upper ends of the rake-bars 10, together with their teeth 34, to or 40 from the slats 11, or change the angularity of said rake-bars with reference to the slats, thereby providing for the proper handling or elevating of various kinds of hay.

For the purpose of providing a means for 45 connecting the hay-loader proper to the rear end of a wagon the tongue 35 is provided, which tongue is pivotally attached to the axle 2, said tongue being provided with the ordinary lateral braces 36, said braces being 50 attached in the ordinary manner. To the top or upper side of the tongue 35 is connected the plate 37, which plate is provided with the slots 38, which slots are for the purpose of receiving the lower portions of the 55 supporting-bars 39, said supporting-bars being pivotally connected to the bar 40, which bar is securely attached to the tie-bars upon which the slats 11 are attached.

Upon the bars 39 is located the sliding head 60 41, to which sliding head is connected the clamping-bar 42, which clamping-bar is for the purpose of binding the sliding head, so as to hold the same at the desired point of adjustment by means of the screw-threaded bar 65 43 and the bar 42.

For the purpose of providing a means for 44 yieldingly holding the hay-loader frame in

the desired position the spring 45 is provided, which spring is located around the bar 46, which bar is connected to the tongue 35 and 70 extends through the sliding head 41, substantially as shown in Fig. 8.

For the purpose of changing the position of the top or upper ends of the bars 39 the bar 40 is provided with a series of apertures such 75 as 47, said apertures being for the purpose of bringing the supporting-bars to or from the top or upper end of the hay-loader frame proper.

It will be understood that when the rake-bars 10 are forced upward at their upper ends they will come in contact with the rollers 23, thereby reducing the friction of said rake-bars and allowing free movement of said bars. 80

For the purpose of providing a means for 85 conveying the hay to the extreme upper end of the frame, the pivoted apron 48 is provided and is pivotally attached to the side members 15 or their equivalents and when not in use remains in the position illustrated in Figs. 1 90 and 2.

When it is desired to hold the apron in an elevated position, the bar 49 is engaged with the spring-bars 50, said spring-bars being provided with the apertures 51, through which 95 apertures the ends of the bar 47 are passed, it being understood that the bars 50 are to be sprung outward when it is desired to connect the bar 49.

The object and purpose to provide spring-bars, such as 50, is to prevent any accidental 100 displacement of the apron.

For the purpose of imparting rotary motion to the compound crank-shaft 9 the sprocket-wheels 52 are provided and are mounted upon the axle 2 in the ordinary manner—that is to say, so that they can be thrown into and out of gear—which construction is common and does not need to be explained and forms no part of the present 110 invention that such wheels must necessarily be provided.

For the purpose of properly connecting the rear ends of the bars 4 together the cross-bar 53 is provided, which is connected to the rear 115 ends of said bars 4, substantially as shown in Fig. 1.

If desired, the bar or brace 53 may be attached to the top or upper ends of the uprights 5, it being understood that said uprights may 120 be extended, so to provide a means for attachment.

In Fig. 5 the brace or bar 53 is not shown; but it will be understood it is to be connected to the rear end of the bar 4, (shown in said figure,) or, as above stated, it may be attached to the top or upper end, as desired. 125

Having fully described my invention, what I claim as new, and desire to secure by Letters Patent, is—

In a hay-loader the combination of a traveling frame, drive-chains extended rearward and under the compound crank-shaft-propelling sprocket-wheels, and over idlers, a com- 130

pound crank-shaft journaled to adjustable bearings, idlers mounted upon adjustable spindles and levers pivotally attached to uprights on the frame and the connecting-plates for said adjustable bearings and spindles, substantially as and for the purpose specified.

5 In testimony that I claim the above I have

hereunto subscribed my name in the presence of two witnesses.

WILLIAM B. KIRKPATRICK.
